UNITED STATES PATENT OFFICE.

WALTER BRAMPTON, OF DORRIDGE, NEAR BIRMINGHAM, ENGLAND.

CYCLE-SADDLE.

SPECIFICATION forming part of Letters Patent No. 695,142, dated March 11, 1902.

Application filed October 26, 1901. Serial No. 80,095. (No model.)

To all whom it may concern:

Be it known that I, WALTER BRAMPTON, a subject of the King of Great Britain, and a resident of Moorside, Dorridge, in the county 5 of Warwick, England, have invented certain new and useful Improvements in Cycle-Saddles, of which the following is a specification.

My invention has for its object improvements in cycle-saddles by which I am enabled 10 to increase their resiliency, thus making them more comfortable for riding.

In carrying my invention into practice I form with or attach to the back or rear of the leather seat of a cycle-saddle an extended or 15 projecting portion or portions of leather, and to the rear edge of this extended portion I fix a metal plate or band to which the rear end or ends of the metal frame of the saddle are secured, the front of the frame being attached to the "nose" or pommel of the saddle in the usual manner. The usual cantle-plate for keeping the leather seat extended or in shape is attached to the seat in the ordinary manner. It will thus be seen that as 20 25 the saddle-seat is suspended in the frame by the extended portion and the pommel end the resiliency of the saddle is increased and the jar or effect caused by the metal frame being connected to the cantle-plate is avoided.

30 In order that my invention may be clearly understood and more easily carried into practical effect, I have appended hereunto a sheet of drawings upon which I have illustrated an example of my new saddle. It must, however, be understood that various forms of 35 saddles and varieties of underframes may be used without departing from the broad principle of my invention.

Figure 1 is a general plan looking upon the 40 leather cover or top A of one of my saddles which shows the extended part A' of the cover. Fig. 2 is an inverted plan of the same saddle, showing a frame and its attachments, but other formations of frames may be used 45 instead of the one shown. Fig. 3 is a part section and part elevation looking at the side of the same saddle.

It will be observed that the underframe F 45 is not directly connected to the cantle-plate P, but to a further or supplemental cantle-plate P', which is much shorter than the usual

cantle-plate P, which extends across the broadest part of the cover A, keeping it in shape, and this plate simply stiffens the leather cover A. The leather cover A, however, extends 55 to the supplemental short cantle-plate P' and is attached and secured thereto by rivets or other fastenings r'. Similar rivets r secure the cantle-plate P to the leather cover. The particular underframe shown to illustrate the 60 principle finishes with coils f' and outward projections f'', which take into ears E, which are fast to the short cantle-plate P, and permit a certain amount of freedom or movement when in use. The connection there- 65 fore between the supplemental cantle-plate P' and the usual cantle-plate P is entirely and wholly made by the extension of the leather covering A', which narrows off to P'. This connection through the leather covering 70 constitutes a most simple means of allowing a restrained movement or oscillation of the cantle-plate P both at its ends and other parts, so as to avoid extreme stiffness or undue looseness. Saddles have been previously 75 tried with spiral-spring extensions to a back cantle-plate; but they were not a success, and other saddles have been tried with a supplemental cantle-plate and lever or rod connections to the same; but I find the best results 80 are obtained in the most simple manner by the extension of the leather or its equivalent covering without any other connection between the frame and the cantle-plate P. The frame carries any of the usual bosses B to 85 fasten to the cycle.

What I claim then is—

In a saddle, a suitable supporting-spring, a curved cantle-plate connected to the rear thereof, a saddle-leather secured to the said 90 plate at its rear end and to the spring at its front end, and a second bar curved substantially concentric with the cantle-plate and secured solely to the saddle-leather in advance of said plate, substantially as described. 95

In witness whereof I have hereunto set my hand in presence of two witnesses.

WALTER BRAMPTON.
